Attorneys

UNITED STATES PATENT OFFICE.

PHILIP E. GABRIEL, OF DETROIT, MICHIGAN.

DIE-CASTING MACHINE.

1,301,788.

Specification of Letters Patent. Patented Apr. 22, 1919.

Application filed October 25, 1916, Serial No. 127,549. Renewed March 7, 1918. Serial No. 281,273.

To all whom it may concern:

Be it known that I, PHILIP E. GABRIEL, a citizen of the United States of America, residing at Detroit, in the county of Wayne and State of Michigan, have invented certain new and useful Improvements in Die-Casting Machines, of which the following is a specification, reference being had therein to the accompanying drawings.

10 My invention relates to casting machines, particularly of the die-casting type, and it is the object of the invention to obtain a construction which has a greatly improved control mechanism. It is another object to obtain a construction in which a portion of the die or mold is removed from another portion at a predetermined time in its travel to permit of the removal of the casting. It is still another object to obtain a construction which 20 will protect the operator; and further to obtain various advantages hereinafter set forth.

Figure 1 is a perspective view of my improved casting machine;

25 Fig. 2 is a fragmentary elevation partly in section of the die or mold operating mechanism;

Fig. 3 is a fragmentary sectional view of the machine showing the operating mechanism for the die or mold supporting table;

30 Fig. 4 is an enlarged sectional detailed view.

A is the base of the machine provided with vertically extending columns B upon 35 which are mounted rigidly the receptacle C containing the molten metal and slidably the table guides D and the apron E, the latter for protecting the operator from the molten metal during the casting operation.

40 The table F longitudinally slidably engages the guides D, said table being provided with a rack F' engaged by the pinion F' which is rotatable by the hand wheel F'. Mounted upon the table is the die or mold H secured thereto by bolts I engaging the inverted T-slots I'. To permit of removing the casting from the die or mold the latter is formed in two parts, the cope and the drag, H' and H² respectively, the drag being secured rigidly to the table and the cope being mounted to move both transversely and vertically relative to the drag. As shown the cope longitudinally slidably engages guides J extending transversely of the drag and

55 mounted upon rods J' passing through the table F and supported upon the yoke J² which slidably engages rods J³ mounted in the member K which is secured to the table F by suitable means to be described later. The link K' is pivotally connected at one 60 end to the yoke J² and at the other end to the bell crank K² rotatably mounted in the member K. The other end of the bell crank is pivotally connected to the rod K³ extending to the rear of the machine and passing 65 through a slot L' in the rod L secured to the rear columns B. A transversely extending pin L² is suitably located in the rod K³ to contact with the rod L to hold the rod K³ stationary at a predetermined point upon the 70 outward movement of the table to vertically move the cope from the drag through the bell crank K², the link K', the yoke J², the rods J', and the guides J.

75 For the purpose of ejecting the casting from the drag or pulling the core from the casting there is provided the plunger N extending through the table F into the drag H² and movable longitudinally by means of a lever M' having a pinion engaging co-operating teeth upon the plunger.

80 The means for securing the member K to the table F comprises the depending member a upon the under side of the table F provided with the pivot rod b extending transversely thereof and upon which the member K is mounted. The bell crank K² is rotatably mounted on this pivot rod. A further function of the depending member a is that of pivotally supporting the lever M' and also 85 protecting the plunger N, said depending member having a hollow portion c for receiving one end of the lever M' and the plunger N.

85 To secure the pour opening in the cope in 90 tight contact with the bottom of the receptacle C containing the molten metal the yoke N' vertically slidably engaging the pin N² is connected to the guides D by means of the rods N³ which adjustably engage the yoke. 95 The pin N² is supported upon its bifurcated base n preferably integral therewith. The toggle linkage comprising the lugs O and O² and the connecting link O' adjust the yoke relative to the pin, the lug O² being part of 100 the bell crank engaged and operated by the lever O'. On the opposite side of the pin N² the link intermediate the two lugs is pro-

vided with an extension O^4 (shown in Fig. 3) to prevent the toggle linkage from going past dead center.

The compressed air used in forcing the molten metal into the die or mold enters the receptacle C through the pipe C' and is controlled by the valve upon the pivot pin C² to which is rigidly secured the rock arm C³. The rod P extending into the receptacle C₄ 10 controls the admission of the molten metal forced by the compressed air into the die or mold, the rod being movable by means of the member P' upon the shaft P². A spring P³ tends to maintain the member P' in the position for retaining the rod in closed position. For operating both the air-controlling and the metal-controlling valves the hand lever Q counter-weighted at Q' and pivoted at Q² to the frame of the machine is provided, 15 there being pivotally connected to the hand lever Q and the rock arm C³ the link R, and to the projection R' of the hand lever and the lug R² on the shaft P² the link R³. In order to operate the metal-controlling valve 20 subsequent to the operation of the air-controlling valve the link R³ is provided with a longitudinal slot R⁴ permitting of lost motion.

The shield E for protecting the operator from molten metal during the casting operation is slidably mounted upon the columns B at the front of the machine so that the shield may be raised above the die or mold when the latter is moved into or out from 25 the casting position and be between the die or mold and the operator when the former is in the casting position. For raising and lowering the shield toggle linkage is provided in which the separate links S and S' 30 pivoted to each other are respectively pivoted to the shield and the frame of the machine with the link S² pivotally connecting the link S' and the rock arm C³.

In operation swinging of the hand lever 35 opens the compressed air valve and lowers the shield and subsequently opens the metal-controlling valve to permit of the entrance of the metal under pressure into the die or mold.

Still another feature is the arrangement 40 for preventing operation of the hand lever Q until the die or mold is clamped in casting position. Secured to the guide D in the path of the hand lever Q is the stop member T 45 provided with a slot T' engageable by the hand lever. When the valves are closed the bolt W normally extends into the path of outward movement of the hand lever Q to prevent the swinging of the same, the bell 50 crank V pivotally mounted upon the member T having one end portion engaging the bolt W to retract the same and the opposite end portion in the path of the rod U rigidly secured to the frame of the machine and extending through the member T. Thus it is

readily apparent that upward movement of the guides D releases the hand lever through the rod U, bell crank V and bolt W so to be free to swing.

In operation the cope is moved over the 55 drag and the table supporting the same is moved inward by means of the rack and pinion engagement, the cope being permitted to fall upon the drag. When the die or mold is in its inner position the table is 60 raised by means of the raising lever and the intermediate connecting mechanism to make a tight fit between the bottom of the receptacle containing the molten metal and the die or mold and at the same time the hand lever controlling the operation of the air-controlling valve and the metal-controlling valve and the shield is released to be free to swing. Upon the swinging of the hand lever the air-controlling valve and the shield are 65 operated and subsequently the metal-controlling valve is operated. When the casting operation is completed the hand lever and raising lever are swung back to their original position, the hand lever then being 70 locked in position by the bolt. The table is moved outwardly by the rack and pinion engagement and when near the end of its outward movement the cope is raised from the drag by means of the rod having the limited return movement and intermediate connecting mechanism. Then the casting may be easily removed by operating the plunger 75 extending into the drag through its lever.

What I claim as my invention is:

1. In a casting machine, the combination 80 with a movable table and means for moving the same, of a die or mold comprising a drag rigidly mounted thereon and a cope slidably mounted thereon, a member beneath said table and secured thereto, a yoke carrying said cope and slidably engaging said member, a bell-crank mounted in said member, connections between one end of said bell-crank and said yoke, and a rod connected to 85 the other end of said bell-crank and having the movement in one direction limited for the purpose described.

2. In a casting machine, a base provided 90 with vertically extending columns, a receptacle for containing molten metal at the opposite end of said columns, a die or mold, a reciprocable table supporting the same, guides for said table slidably mounted on said columns, a pin upon said base, a yoke 95 slidably engaging said pin and connected to said guides, and toggle linkage for operating said yoke.

3. In a casting machine, a base provided 100 with vertically extending columns, a receptacle for containing molten metal at the opposite end of said columns, a die or mold, a reciprocable table supporting the same, guides for said table slidably mounted on 105 said columns, a pin upon said base, a yoke 110 slidably engaging said pin and connected to said guides, and toggle linkage for operating said yoke.

slidably engaging said pin and connected to said guides, toggle linkage for raising and lowering said yoke, and means for preventing said toggle linkage from passing dead center.

4. In a casting machine, the combination of horizontally-extending guides, a table member movable longitudinally of said

guides, a die or mold comprising vertically separable parts, one of said parts mounted on said table member, and means for separating said parts at a predetermined time of movement of said table member upon said guides.

In testimony whereof I affix my signature, 15
PHILIP E. GABRIEL.
